HAIR WAVING MECHANISM

Oliver A. Harrell, Little Rock, Ark.

Application January 5, 1948, Serial No. 585

5 Claims. (Cl. 132—36)

1

My invention relates to hair waving machines and it is an object of the same to provide means for use with hair waving machines by the use of which the making of spiral curls on a machine designed for making Croquignole curls or waves shall be facilitated. It is well known that spiral curls were popular before Croquignole waves came into vogue, and that machines were devised for curling the hair in spirals and setting the curl before Croquignole machines were invented, but neither type of machine was well suited to do the work for which the other type was designed. The old spiral machines were also highly objectionable by reason of the exposed character of their "bakers" which had exposed surfaces that became very hot, giving rise to danger of burns and causing much discomfort both to the users and their customers, even though no burns resulted. It is an important object of my invention to render it easy to make spiral curls upon Croquignole machines of conventional design by providing simple and inexpensive attachments that can be used with such machines for said purpose.

Another object of the invention is to provide means for the making of spiral curls with much less discomfort and danger of burns, e. g., the well-known "pull burns" incidental to spiral curling operations.

Another object is to provide an attachment for the clamps of a Croquignole machine that shall be quickly and easily applicable when spiral curls are desired, and quickly and easily detachable therefrom.

Referring to the drawings, which are made a part of this application and in which similar reference characters indicate similar parts:

Fig. 1 is an elevation showing the device of my invention applied to a Croquignole clamp,

Fig. 2, an elevation at right-angles to Fig. 1, and

Fig. 3, an elevation of the attachment separated from the clamp.

In the drawings, reference character 10 indicates a supporting body of a conventional hair spindle clamp, said body being of elliptical shape in cross section in a plane at right angles to the paper in Fig. 1 and being made of hard rubber or the like insulating material. A shell 11 is connected to the lower end of the body and this shell consists of aluminum or similar light metal, it being approximately semi-cylindrical and aligned with the major axis of the body. Inside the shell and concentric therewith but projecting at its side and end edges there is a shell 12 of heat-conductive material such as steel which is rigidly se-

2

cured to the outer shell and a heating element (not shown) is confined between the concentric shells, said heating element being electrically heated by means of a conventional double-strand electric wire 13, and a ground connection 13', each wire leading to a suitable source of electricity.

In the use of the clamp for the usual Croquignole curls a tress of hair, which is of a width horizontally or crosswise of the customer's head more or less corresponding to the length of a hair spindle that is to be gripped by the clamp while the setting of the curl is proceeding under heat, is wrapped or wound upon the spindle, the width of the tress being such as to cover the entire length of the spindle or substantially so, in each wrapping or convolution of the hair and the wrapping beginning at the ends of the hair.

It is an object of the clamp herein shown to protect the customers against the heat of the shells against which the hair on the spindle is pressed during treatment and the clamp is therefore provided with suitable jaws 14, 14, more fully disclosed in my co-pending application Serial No. 755 519, filed June 18, 1947, granted as Pat. No.

2,515,512 said jaws being spaced at all times from the heated shells 11, 12, but substantially enclosing a wound hair spindle and its wrappings, the free edges of said jaws nearly meeting adjacent the scalp. The jaws are operated by handles

15, 15 of insulating material mounted on resilient lateral projection 16' that are integral with the jaws and with an endless band of spring metal 16" encircling the body 10. The spring metal forces the jaws toward one another, while forcing the handles away from each other. Thus the handles will open the jaws when pressed towards one another. In the making of spiral curls a small lock of hair, which hair is often, though not necessarily, longer than in the case of

Croquignole curls, is segregated close to the scalp and is wound in a true spiral or helix lengthwise of a spindle the helix beginning at one end of the spindle and ending at or near the other end of the same, and the wrapping operation beginning at the roots of the hair instead of at the outer ends thereof. When the spiral is completed the free ends of the hair in that lock are secured to the spindle and the wrapped spindle is inserted endwise into a cylindrical shell of

heat-conducting material and heat is applied to set the curl. Commonly, when the hair was worn longer, the spindles used were longer than those used for Croquignole curls, but that is not necessary as spiral curls can be made equally well with hair of length suitable for Croquignole curls.

In order that clamps, such as used for Croqui-

gnole curls, may be used in making spiral curls it is necessary, or at least highly desirable, that the spindles and clamps be held in a position at right-angles to their normal position, i. e., with the spindle vertical instead of horizontal alongside the head. With that end in view I have devised a hair clamp supporting device comprising a strip 16 preferably made of spring metal such as spring steel, which strip is bent at one end, as at 17, to embrace a portion of the body 10 of the hair clamp.

A jaw 18 in opposed relation to jaw 17 embraces the opposite side of the body 10 and this jaw has integral with it a supporting portion in the form of a slide 19 surrounding the mid-portion of strip 16 more or less completely. A bracket 19' has a projecting arm 20 with a hole for guiding a rod 21 fixed at its lower end to the jaw 18, said bracket being fixed to strip 16 as by means of bolts 22. A collar 23 on the rod limits its downward movement, said rod and jaw being biased to move toward jaw 17 by a coil spring 24 encircling the rod and bearing at its ends respectively against arm 20 and jaw 18.

The striplike body 16 is provided at its upper end with a guide 25, shown as consisting of a flat strip secured at one end to the strip by a bolt 26 and bent approximately into elliptical form for engaging wires 13 and holding the parts in the position illustrated, or substantially so. It will be understood that in both spiral and Croquignole machines the "bakers" are on wires depending from an overhead support e. g. in machines such as shown in patents to Roos, 1,206,917; Blum, 1,560,894; and Dorange, 1,666,169, and thus, by the use of my device the hair clamps will be held in the position best illustrated in Fig. 2, with the spindle upright so as to produce the best effects of the heat on the hair wound thereon, for the production of lasting spiral curls or waves.

In the use of the device of my invention, it is simply placed by hand with the jaw 17 against one side of the body 16 of the hair clamp as shown in Fig. 2, and then forced lengthwise of itself so as to compress the spring 24 and move the jaw 18 along the strip 16 as a guide, until the jaws are sufficiently separated to permit jaw 18 to move into the position illustrated in Fig. 1, after which the pressure of the operator's hand is removed so that the jaws can be made to grip the body 10 by the pressure of spring 24. Now the wires 13 are placed in the position shown in Figs. 1 and 2, whereupon the hair clamp assumes the vertical position shown in Fig. 2 and so will hold a spindle with a spiral of hair wound thereon in similar position. The current being then turned on to heat the baking means, the operation proceeds until the curl is set. It will be seen that the operator's hands need not approach close to the heated parts of the baker, either in manipulating the jaws or in opening the clamping jaws 17, 18.

It will be obvious to those skilled in the art that many changes may be made in the devices herein disclosed, all without departing from the spirit of the invention; and therefore I do not limit myself to what is shown in the drawings and described in the specification, but only as indicated in the appended claims.

Having fully described my invention, what I claim is:

1. In a permanent wave apparatus of the type having an overhead support, a body elliptical in

cross section, semi-cylindrical heating means fixed to one end of the body and aligned with the major axis of the same, pivoted spring-pressed jaws for holding a wound hair spindle, said jaws being mounted on said body and having opposed edges in parallelism to said axis, electric conductors connected to said heating means and depending from said overhead support, the combination of a long handle of spring metal, relatively slidable jaws on said handle shaped to engage about the elliptical part of said body to hold said handle parallel to said major axis, one of said relatively slidable jaws being integral with said handle, a support for the other jaw slidable on said handle, a flange projecting from said handle, a stem on the last-named jaw slidable through a hole in said flange, a coil spring about said stem between the flange and the last-named jaw, and a clip affixed to the end of said handle at the end remote from the heating means for engagement with a conductor to hold said handle in line with the conductor.

2. In a permanent waving apparatus of the type having relatively movable pivoted jaws for embracing a wound hair spindle, heating means aligned with a hair spindle in said jaws, a body supporting said heating means and said jaws, an overhead support, and electric wires depending from said support, the combination of a long flat handle of spring metal, relatively slidable jaws on said handle shaped to engage about the elliptical part of said body to hold said handle parallel to the major axis, one of said relatively slidable jaws being integral with said handle, a support for the other jaw slidable on said handle, a flange projecting from said handle, a stem on the last-named jaw slidable through a hole in said flange, a coil spring about said stem between the flange and the last-named jaw, and a clip affixed to the end of said handle at the end remote from the heating means for engagement with a conductor to hold said handle in line with the conductor.

3. In a permanent wave apparatus of the type having an overhead support, a body elliptical in cross section, semi-cylindrical heating means fixed to one end of the body and aligned with the major axis of the same, pivoted spring-pressed jaws for holding a wound hair spindle, said jaws being mounted on said body and having opposed edges in parallelism to said axis, electric conductors connected to said heating means and depending from said overhead support, clamping means comprising an elongated handle having jaws shaped to engage said body and hold it in position to align a hair spindle in said first-named jaws with said elongated handle, one of said last-named jaws being fixed and the other jaw sliding on said handle, spring means for urging the last-named jaws into holding position, and a clip at the end of said handle remote from its jaws for engagement with said wires for holding the handle approximately in line with said wires.

4. A device as in claim 3, wherein said handle is resilient.

5. In a permanent wave apparatus of the type having an overhead support, a body elliptical in cross section, semi-cylindrical heating means fixed to one end of the body and aligned with the major axis of the same, pivoted spring-pressed jaws for holding a wound hair spindle, said jaws being mounted on said body and having opposed edges in parallelism to said axis, electric conduc-

tors connected to said heating means and depending from said overhead support, an elongated handle having opposed spring-pressed jaws at one end to engage said body and hold it in position to align a wound hair spindle in the first-named jaws with said elongated member, and a clip on said elongated handle remote from its jaws for engaging the wires to hold said elongated member in alignment with said wires.
